(57) **CLAIM**

The ornamental design for a spray pump, as shown and described herein.

DESCRIPTION

FIG. 1 is a top front perspective view of the spray pump showing my new design;

FIG. 2 is a top rear perspective view thereof;

FIG. 3 is a top plan view thereof;

FIG. 4 is a rear elevational view thereof;

FIG. 5 is a side elevational view thereof; and,

FIG. 6 is a front elevational view thereof.

The broken lines are included for the purpose of illustrating the portions of the spray pump that form no part of the claimed design.
